TABLE ORNAMENT OR SIMILAR ARTICLE

Lemuel D. Swearingen, Detroit, Mich.

Application January 28, 1957, Serial No. 44,640

Term of patent 7 years

(Cl. D29—1)

Fig. 1

Fig. 1 is a front elevational view of a table ornament showing my new design.

Fig. 2 is a side elevational view thereof with a portion of the circular base broken away for convenience of illustration.

I claim:

The ornamental design for a table ornament or similar article, as shown.
